UNITED STATES PATENT OFFICE

104,598

DESIGN FOR A MATTRESS

Sidney E. Blumenthal, New Orleans, La.

Application May 11, 1936, Serial No. 62,600

Term of patent 7 years

To whom it may concern:

Be it known that I, Sidney E. Blumenthal, a citizen of the United States and a resident of New Orleans, in the county of Orleans and State of Louisiana, have invented a new, original, and ornamental Design for a Mattress, of which the following is a specification, reference being had to the accompanying drawing, forming a part thereof.

In the drawing:

The figure is a perspective view of a mattress showing my design. The salient feature of the design resides in the groups of linklike strands extending transversely across the top and bottom of the mattress.

I claim:

The ornamental design for a mattress as shown and described.

SIDNEY E. BLUMENTHAL.
